PLUG

Laurence E. MacGregor, Long Beach, Calif.

Application March 7, 1939, Serial No. 260,325

9 Claims. (CL 166—1)

This invention relates to plugs, particularly to a type of plug for use in well casing.

This invention has for an object the provision of a device which may act as either a heaving 5 or bridge plug; and when so acting in either or both of said capacities, produces efficient results.

A further object of the invention is the provision of a plug of the character stated, which may readily enter a casing, be positioned therein 10 at any desired location without using any special setting tools, and which device when positioned does not require slips or other like devices for holding the plug in position.

Another object is the provision of a plug of 15 the character stated, so constructed and arranged as to be readily broken up or drilled out when the use for such a plug is no longer necessary.

Another object is the provision of a plug which permits circulation therearound during the lowering of the plug within a well casing.

Other objects of the invention include a plug which is simple of structure, inexpensive in cost of manufacture, capable of producing superior results in actual use and service, which is easily 25 positioned within a casing, and is easily removed from the casing as it may be readily broken up and then bailed out in the usual manner.

With the above mentioned and other objects in view, the invention consists in the novel and useful provision, formation, construction, association, and relative arrangement of parts, members and features, all as depicted in a certain embodiment in the accompanying drawing, described generally, and more particularly pointed 35 out in the claims.

In the drawing:

Figure 1 is a transverse longitudinal sectional view of casing, with the improved plug positioned therein and cement slurry poured on top of the 40 plug.

Figure 2 is a fragmentary sectional view on the line 2—2 of Figure 1, and,

Figure 3 is a transverse sectional view on an enlarged scale on the line 3—3 of Figure 1.

Referring now with particularity to the drawing, the improved plug as an entirety is designated by the numeral 1. This plug is adapted to be positioned within casing 2 and at any desired location therein, or within the liner, dependent 45 upon use and service.

The plug includes two guides 3 and 4 held in spaced axial alignment by an interconnecting tubular member 5. Both guides are longitudinally bored, as shown at 6 and 7, to receive reduced diameter portions of the tube 5. Both

guides may be provided with longitudinal slots or flutes, as shown at 8. These slots act as circulation ways or passages. Either one or both of the plugs is adapted to carry at one end thereof a disc 9. This disc in the embodiment shown 5 may be formed of rubber and is held to the end of the plug by any suitable means, such as by a screw 10. To prevent tearing of the disc 9, a cup-type metal member 11 may be placed against the outer surface of the disc, through 10 which cup and the rubber disc the screw 10 has threaded engagement with the guide.

The tube 5 is provided with spirally arranged transverse bores 12. Wires either in bundles or singly are passed through said bores, with ends 15 of said wires extending equal distances beyond the periphery of the tube as, for instance, illustrated for one bundle of wires at 13. After all the wires have been assembled, as shown in Figure 1, some suitable means, such as lead, Babbitt, 20 cement, or other material, is poured within the tube 5 and prior to connection of said tube with the guides 3, which material will surround the wires and hold the same in position and against transverse movement through said openings in 25 the tube. The length of the wires is preferably greater than the diameter of the liner or of the casing, to the end that the wires bend upwardly as the plug as an entirety is forced downwardly within the casing or liner. The guides 3 and the tube 5 may be formed of wood or the device may 30 be manufactured from aluminum, or other metal.

The operation, uses and advantages of the invention just described are as follows:

If we assume that a casing has been positioned 35 within a well hole, and through some suitable system, such as a "Stratograph", oil sand has been detected at some region through which the casing has passed, and a test to determine the extent of the oil is desired, or if for some reason the bottom oil sands have become unproductive and other oil sands have been located, through 40 which the casing passes, the plug may be moved downwardly within the casing through the medium of a sinker bar attached to the sand line, 45 or in practice, the drill pipe may be used to move the plug downwardly to any desired position. The wires frictionally engage the inner surface of the casing, to the end that the plug will remain at any desired position therein. Cement slurry, such as 50 shown in Figure 1 at 14 may then be poured within the casing, and the rubber disc will hold the slurry against movement therewith, as shown.

If we assume that the casing is filled with fluid prior to entrance of the plug therein, it is evident 55

that the plug may nevertheless be lowered within the casing in the manner stated aforesaid, due to the fact that fluid may pass through the flutes or channels in the guides, and the wire members present no appreciable obstruction to movement of said fluid. The cup-shaped disc 9 will readily allow passage of fluid thereabove, as is self-evident. However, this cup-shaped disc restricts passage downwardly as the cup tends to move outwardly into close engagement with the inner wall of the casing. After cement slurry has been positioned thereon and allowed to harden, perforating of the casing is a mere matter of selection of proper perforating apparatus, and a test may be made of the particular sands. If the sands do not yield oil, the cement may be drilled out or broken up in the usual manner and due to the construction of the particular plug, being of wood or aluminum, it is easily broken up, and may be removed or left in the well hole. The removal may be accomplished through the means of a fishing tool in the usual manner.

The device acts either as a bridging or heaving plug. By "heaving", I refer to unconsolidated productive sand, which tends to heave or flow into the well with the oil, often filling the hole for several hundreds of feet above the bottom of the well, thereby requiring either a reborning or prolonged bailing. As before stated, this plug may function in the capacity of a heaving plug, to the end that heaving is prevented.

If we assume that the plug without the disc 9 is at the bottom of the well hole, the guide 4 being directly above the bull nose or shoe, which is usually attached to the end of the liner, sand which would tend to heave would be thereby prevented from entering the liner through the simple expedient of pouring cement or other substance down over the plug and between the guides 3 and 4, said material surrounding the wires and the interconnecting member 5.

Its use as a bridging plug has been described. In other words, the plug in the showing of Figures 1 and 2 acts in the capacity of a bridging plug, in that it provides a support for the cement slurry.

As a further example of the use of the improved plug, the plug may be moved downwardly to a selected position within the casing or liner. A bailing operation may take place and when the bailer reaches bottom, a mark will be made upon said bailer when it strikes the top of the plug, particularly if the plug is formed of some metal, such as aluminum or brass. This marking on the bailer will indicate the position of the plug with respect to the depth of the bailing operation. Furthermore, the plug acts to save the bull nose or shoe of the liner, in that the plug will prevent the bailer from suddenly dropping straight through the casing and liner and hitting the bull nose, knocking it off or breaking it.

In certain installations, it is not necessary to flute the guides, as there may be sufficient clearance between the periphery of the guides and the inner surface of the casing to permit circulation past the plug. This would be the case for

the showing of Figures 1 and 2, although the guides are of fluted construction.

I claim:

1. In a heaving and bridging plug construction, two spaced guides, an interconnecting member therebetween, and wire members secured to the interconnecting member and radially extending beyond the periphery thereof.

2. In a bridging and heaving plug, a tubular member, guides at each end of the tubular member, wires diametrically passed through said tubular member with ends of said wires extending beyond the periphery of the tubular member, and means for securing said wires to said tubular member.

3. In a bridging and heaving plug, a tubular member; a substantially cylindrical guide secured at each end of said tubular member, and wires passed through said tubular member, the length of said wires being greater than the diameter of the guides.

4. In a bridging and heaving plug, a tubular member, end guides secured to said tubular member, transverse wires passed through said tubular member, and means within the tubular member and surrounding said wires for holding said wires to said tubular member.

5. A bridging and heaving plug adapted to be positioned within a casing or liner, including a pair of spaced apart guides, an interconnecting member between said guides, and wire members passed through said interconnecting member for frictional engagement with the inner surface of said casing or liner.

6. A plug adapted to be positioned within a casing or liner, including a tubular member, guides for each end of said tubular member, said guides being longitudinally fluted to provide circulation ways, wire members passed through said tubular member for frictional engagement with the inner surface of said casing or liner, and means carried by said plug for restricting passage of fluid in one direction when the said plug is positioned within said casing or liner.

7. In a bridging and heaving plug, a tubular member, substantially cylindrical end guides secured to said tubular member, transverse wires passed through said tubular member, and a sealing means within the tubular member for securing the wires in position.

8. In a heaving and bridging plug construction, two spaced substantially cylindrical guides, an interconnecting tubular member therebetween, and a flexible disc secured to one end of a guide and of greater diameter than the said guide.

9. In a heaving and bridging plug, two spaced guides, an interconnecting member therebetween, and wire members secured to the interconnecting member; said plug adapted to be positioned within a casing or liner, and the said plug constructed of a material adapted to mark any instrumentality dropped through said casing or liner and impacting said plug.

LAURENCE B. MACGREGOR.
